UNITED STATES PATENT OFFICE

THOMAS F. GAYNOR, OF LOUISVILLE, KENTUCKY, ASSIGNOR TO THE GAYNOR ELECTRIC COMPANY, OF SAME PLACE.

ELECTRIC SWITCH.

SPECIFICATION forming part of Letters Patent No. 406,897, dated July 16, 1889.

Application filed January 23, 1888. Serial No. 261,636. (No model.)

To all whom it may concern:

Be it known that I, THOMAS F. GAYNOR, a citizen of the United States, residing at Louisville, in the county of Jefferson and State of Kentucky, have invented new and useful Improvements in Electric Switches, of which the following is a specification, reference being had therein to the accompanying drawings.

My invention has for its object to improve 10 that class of electric switches and lightning-arresters in which plugs are usually inserted in holes between the plates to make the proper electric connections by substituting for said plugs, which are liable to be misplaced or 15 which may drop out of their positions between the plates, a permanently-pivoted lever having a suitable spring-bearing to make a sliding contact with the plate to be connected, a handle by which the lever is properly adjusted, a stop device by which the lever is arrested and held in its proper position, an end so designed as to indicate the nature 20 of the connection made, together with a printed or otherwise marked design by which 25 the nature of the connection may be read and observed.

My object is also to so design the parts and 30 designate their office that persons inexperienced in the management of electric appliances may readily know at a glance the proper office of each of the parts of the switch and be enabled to quickly make the connections and changes desired.

The invention will be more fully understood 35 from the following description in connection with the accompanying drawings.

Figure 1 is a front elevation of an electric switch provided with my improvements. Fig. 2 is a vertical section through the line *a b*, 40 Fig. 1. Fig. 3 is a cross-section of the lever through the line *c d*, Fig. 1. Fig. 4 is the circuit-wheel mechanism of an electric signal-box. Fig. 5 is a modified construction of the index parts of the invention. Fig. 6 is a 45 modified construction of the lever. Fig. 7 is a sectional view through the handle of Fig. 6. Fig. 8 is a section through the line *e* and *e'* of Fig. 1.

In the drawings similar letters refer to 50 similar parts throughout the several views.

The letter *A* indicates a base of hard rubber or other insulating material, to which the other parts of the switch are attached by screws, as shown at 20 21 22.

B represents a metal plate, to which one end of the conducting line-wire *f* of the circuit is attached through the binding-post *m*.

C represents another metal plate, to which the other end of the line-wire *f'* of the circuit is attached through the post *n*.

o represents a post, to which a local or instrument line-wire *i* is connected to plate *C*.

q is the post by which the other end of the local wire *i'* is connected to plate *B*.

u u u u represent binding-screws. 65

L represents a switch-lever, which is pivoted upon the center stud *H*. The screw *P* keeps the lever *L* in place upon the stud *H*. A proper tension upon the lever is made by the friction-washer *w*. 70

S indicates a hard-rubber handle screwed tightly upon the lever by means of the screw *x*. The head of the screw *x'* is convex, and is pressed into the countersunk stop-holes *K K K* by the tension of the friction-washer *w*. 75

The lever *L*, when turned around upon its pivot *H*, causes the head of the screw *x'* to pass out of the stop-holes *K K K* and slide upon the plates *B C G* beneath. The lever, with all its metallic attachments, is insulated from the plates *B C G* by the base *A*, except 80 where the contact-spring comes in contact therewith. The outer end of the lever *L* terminates in a pointer *j*. Upon the face of the base, near its periphery, printed or stamped letters, figures, or characters are placed, which 85 indicate the connection made by the switch-lever when the latter points to them.

ZZZ represent screws in holes through the base *A* to attach the whole instrument to the machine or fixture where it is to be used. 900

The numerals 1 2 3 4 show where indices may be placed upon the plates B C, instead of upon the base, if desired.

Fig. 4 shows the circuit-breaking wheel and contact-springs of an electric signal-box. The clock-work may be of any ordinary or well-known construction, so is consequently omitted. Reference may be had, however, to my application for Letters Patent for an improved electric signal-box of even date herewith, in which the utility and application of my improved switch may be more fully seen and understood, together with a complete signal-box mechanism.

Fig. 5 shows a modified construction of the index parts of the switch. Any other suitable arrangement can be used in which the index and index-characters can be made to coincide.

The advantages and operation of the switch are as follows: The instrument is placed to best advantage when it is attached to its support in such a manner as to bring its face in a vertical position, as the normal position of the lever L is then perpendicular, which suggests to the observer that the local mechanism is in circuit and that the connections are correct. This is supplemented by the index-word, which in the drawings is "In," to which the pointer directs the eye. The spaces 13 and 14 between the ground-plate G and the plates B and C are also in such positions that metallic particles are not liable to fall into them and make ground-connections with the plates B and C; so, also, for the same reason, are the plates B and C separated by an almost vertical space at 15. By means of the handle S the switch can be quickly moved to any other position—as, for instance, to the position indicated by the indexed words "Out," "Grounded right," "Grounded left," &c.—and the connection required to be made is plainly shown by the coincidence of the pointer and the index-characters. The stop-holes K K K hold the lever in proper position when the adjustment is made. In the drawings the vertical position of the lever brings the contact-spring y entirely upon the plate C, so that, being insulated otherwise, it has no effect upon the circuit which is from the battery 18 to the line f', to post n, through plate C to post o, through local line i to post 16, through contact-spring 12, through wheel 10 to contact-spring 11, to post 17, through line i' to post q, through plate B to post m, to line f, to battery 18.

When the lever is moved to position indicated by the word "Out," then the local line in which the circuit-wheel is shown is short-circuited, the circuit being from plate C through the contact-spring y to plate B to line f, thus practically cutting out of circuit the local loop i i', so that the mechanism therein may be taken out entirely without affecting the main circuit f f'.

When the lever is brought to a horizontal position to the left or to the right, (indicated

by the words "Grounded left" or "Grounded right,") the plate B or plate C is connected with the ground-plate G through the lever 70 contact-spring y, which rests upon the ground-plate G and one of the plates B C, thus establishing a ground-connection for the line-wire f f' through post t and ground-line i', and "short-circuiting" the local line i i'. In other 75 words, if the switch is set upon the words "Grounded right," it signifies that the part of the main line to the right of the switch has a ground-connection therewith. The left leg of the circuit may be opened anywhere between post q and battery 18 and the local line taken out of circuit.

When the switch is set to the left, the above conditions are reversed. Again, if it is desired to put the instrument-line into the 85 main circuit, and the main line is to be grounded upon the right of the instrument, (or on the left, as may be wished,) the setting of the switch-lever to the proper index-words would indicate that the correct connection 90 was made. When this kind of a connection is to be made, the line-wire is disconnected from the binding-post of the plate upon which the lever contact-spring is resting, thus cutting off all connection with that part of the 95 main line. The switch is also a lightning-arrester, as the atmospheric electricity can pass from the line, through plates B or C, to the serrated edge of the ground-plate G, thence to the ground.

A modification of the lightning-arrester is shown in the screw arrangement shown at 19 in Figs. 1 and 8, by which the adjustment may be made very accurately, if desired.

The switch-lever and the contact-spring 105 may be integral, as shown in Figs. 6 and 7, or the lever may be made to bear directly upon the plates or upon springs affixed thereto, without departing from the plan of my invention, as I do not limit myself to the particular manner of construction shown in the drawings.

It can be seen that the lever with the two line-plates, or with either one of the line-plates and the ground-plate, may be made to 115 close the circuit and make a complete instrument.

In Fig. 1 the dotted lines show the plate B as having a ground-connection with the center plate G through the lever L, and the index-words are such as are appropriate for an electric signal-box, more fully described in my application for Letters Patent of even date herewith; but it is obvious that the ground-plate G can be made the terminal of another metallic circuit, in which other electrical apparatus could be placed, if desired. So, also, other instruments could be placed in the instrument-loop i i', in which the circuit-wheel mechanism is shown, or else substituted therefor.

The switch can be used for any telegraph or electric-light circuit, or for any purpose where electric switches are usually employed.

BEST AVAILABLE COP

The index and index-characters can be changed to suit the proper conditions.

By the term "insulating-base" I mean a base of electrically-insulating material which not only insulates the parts of the switch from each other, but also insulates the whole instrument from the support to which it is affixed when in use.

By the term "plate" herein used I mean any metallic material that is provided with the connections and terminals substantially as described.

I claim—

In an electric switch, an insulating-base, 15 in combination with two line-plates, a ground-

plate, and a pivoted contact-lever having a spring-tension contact upon the plate and provided with a stop projection, the plates having registering stop-holes for the stop projection of the lever to enter into, the base 20 or plates having characters which designate the nature of the connection made when the index of the lever is brought into registering position therewith, substantially as described.

THOMAS F. GAYNOR.
